(57) **CLAIM**

The ornamental design for a blood glucose injection recorder, as shown and described.

DESCRIPTION

FIG. 1 is a front perspective view of a blood glucose injection recorder, in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof, wherein the broken lines in FIG. 7 illustrate portions of the blood glucose injection recorder that form no part of the claimed design.
